UNITED STATES PATENT OFFICE.

GEORGE F. GMINDER, OF NEW YORK, N. Y.

DESIGN FOR TRIMMING.

SPECIFICATION forming part of **Design No. 14,665, dated February 12, 1884.**

Application filed December 29, 1883. Term of patent 3½ years.

To all whom it may concern:

Be it known that I, GEO. F. GMINDER, of New York, in the county of New York and State of New York, have invented a certain new and useful Design for Trimming; and I do hereby declare that the following is a full, clear, and exact description thereof, reference being had to the accompanying drawing, and to the letters of reference marked thereon, which form part 10 of this specification.

This invention relates to chenille fringe or trimming; and it consists in the design for the same, which will now be fully described with reference to the drawing, which represents a 15 front view of my fringe or trimming.

A designates the heading of the fringe, which is provided with pendants B, arranged in sections of three, alternately, with single pendants C. The pendants B are what is known as 20 "figured chenille"—that is, they are provided with enlargements or ornaments, which may be of ball, diamond, or any other suitable shape. The intermediate pendants, C, are provided with laterally-projecting figures D,

which are of the oblong or elliptical shape 25 clearly illustrated in the drawing. These figures or ornaments will, as shown, depend over the pendants B, thus forming an attractive and effective pattern.

I claim—

1. The design for chenille fringe or trimming, which consists of figured pendants depending from a heading, and alternating with pendants having laterally-projecting depending figures or ornaments, as set forth. 30

2. The design for chenille fringe or trimming, which consists of figured pendants depending in sections of three from a heading, and alternating with single pendants having laterally-projecting oblong depending figures 40 or ornaments, as set forth. 35

In testimony that I claim the foregoing as my own I affix my signature in presence of two witnesses.

GEORGE F. GMINDER.

Witnesses:

JESSE WILKINSON,
W. K. SECORD.
